UNITED STATES PATENT OFFICE.

FREDERICK REINHARD, OF JERSEY CITY, NEW JERSEY, AND PIETRO GENCHI, OF NEW YORK, N. Y.

MUSICAL INSTRUMENT.

No. 831,471.

Specification of Letters Patent.

Patented Sept. 18, 1906.

Application filed September 7, 1905. Serial No. 277,306.

To all whom it may concern:

Be it known that we, FREDERICK REINHARD, a resident of Jersey City, in the State of New Jersey, and PIETRO GENCHI, a resident of New York, in the State of New York, citizens of the United States, have jointly invented a certain new and useful Musical Instrument, of which the following is a specification.

10 Our invention relates to musical instruments in appearance resembling a harp, but constructed in such a manner as to produce harmonious tone effects, facilitating the grouping of accompaniment with melody strings and restricting the size of the instrument so that a large range of effects may be obtained without making the same burdensome or complicated.

In the drawings, Figure 1 is a front view of 20 the new instrument, partially broken away to show the construction of the two sounding boards. Fig. 2 is a side view of the instrument, and Fig. 3 a front view thereof as it appears when Fig. 1 is reversed.

25 The body A of our instrument is constructed of wood and is given the ornamental appearance shown in Fig. 1. This body is composed of a hollow base, solid side arms rising therefrom, and a solid cross member 30 connecting the upper ends of said arms, all of said parts of the body inclosing an opening between them. At the bottom of this instrument is arranged a sounding-box having two faces B and C for the melody-strings and 35 accompaniment-strings, respectively, the sounding-board C vibrating under the influence of the accompaniment-strings D fairly independent of, yet also slightly effected by, the action of the melody-strings E. The re-

40 verse is true on the opposite side B of the sounding-box. The space between the two face-plates B and C of the sounding-box is unobstructed, so that the vibrations may travel freely through the air from one face-plate to the other. The melody-strings E and 45 accompaniment-strings D are preferably arranged at an angle to each other, as shown in Fig. 1, forming a skew arrangement—that is, they are neither parallel nor convergent—50 and this is of material advantage in playing the instrument, as each melody-string will be distinctly visible from the side on which the accompaniment-strings are arranged through the opening G referred to hereinafter. Lo-

cated centrally with reference to the sound- 55 ing-box B C is the opening F, which is shown in the drawings as on that face of the instrument below the accompaniment-strings. We prefer, however, to place this opening on the opposite face of the box, so that the accom- 60 paniment-chords will act through it toward the melody-strings. The drawing has in this regard been made for the purpose of convenience in visualizing the various strings of the instrument. As will be seen from Fig. 65 1, the accompaniment-strings are arranged in groups of four, with a heavy or deep base-string marking the beginning of each accompaniment-chord. This arrangement makes playing easier, inasmuch as the fingers of the 70 performer will not have to select each element of the desired chord, but finds them right at hand as soon as the basic accompaniment bass note has been struck. For the purpose 75 of further facilitating the playing of this instrument a large open space G is provided between the two series of strings, so that when the melody-strings are uppermost—that is, facing the eye—whatever the position of the instrument the performer can see through 80 the strings and watch the hand which plays the accompaniment select the correct chord. The melody-strings are arranged over bridges H I. (Shown in Fig. 3.) These bridges are disposed at an angle toward each other, so as 85 to permit a greater range of scale. The size of this instrument may vary; but we have found that an instrument from two to two and one-half feet in height can be readily and 90 conveniently transported, particularly when partially supported by means of a ribbon about the neck of the performer, and that it will produce a tuneful and harmonious effect 95 not heretofore achieved by any wire-stringed instrument known to us.

Instead of a sounding-box it is possible to have one or two single sounding-boards, and in the claims we refer to such a structure as the equivalent of a sounding-box. By divid- 100 ing the strain due to the tension of the strings we prevent the instrument from warping and keep it in tune more readily than if all the strings were on one side. It will be seen by looking at Fig. 3 that the planes in which the melody-strings E and the accompaniment- 105 strings D, respectively, are arranged, are parallel in their substantial entirety—that is, from one fastening to the other, said fasten-

ings for the ends of the strings being located on the parallel face-plates B C. The strings are preferably so secured to the instrument that only their lesser portions will be in registry with or adjacent to the sounding-box or sounding-chamber.

What we claim, and desire to secure by Letters Patent, is—

1. A musical instrument comprising a body having an opening extending from one side thereof to the other and two sets of strings, one on each side of the body and across said opening, the strings of each set being parallel to each other, but askew with reference to the strings of the other set.

2. A musical instrument comprising a body having an opening extending from one side thereof to the other and two sets of strings,

one on each side of the body and across said opening, the strings of one set being askew with reference to those of the other set.

3. A musical instrument comprising a body having an opening extending from one side thereof to the other, and two sets of strings arranged in parallel planes on opposite sides of said body and across said opening, the strings of one set being askew with respect to those of the other set.

In witness whereof we have hereunto subscribed our names, in the presence of witnesses, on this 6th day of September, 1905.

FREDERICK REINHARD.
PIETRO GENCHI.
